GRIP GAUGE FOR GOLF CLUBS

John F. Sullivan, Oakland, Calif.

Application August 12, 1938, Serial No. 224,555

6 Claims. (Cl. 33—179)

This invention is a golf grip gauge for use in taking the measurements of a player's hands for the purpose of selecting a golf club having a grip of adequate size or as an aid in the reconstruction 5 of the grip to meet the needs of the individual player.

It is a well-known fact that in the manufacture and sale of golf clubs it has been the standard practice to make all golf clubs with uniform grips 10 despite the fact that requirements for different players may run the gamut of hand sizes. It has also been the practice, when a player requires a grip of a size different from that in which manufactured, for the professional to break the individual grip down and rebuild them as nearly as possible to the desired size.

These practices do not make for efficiency. In the first place it is far more desirable for the individual player's hands to be measured and to 20 supply him with factory built clubs according to his specifications and in the second place the individual club maker usually does not have the facilities for uniformly carrying out the players wishes with respect to the size of the club grip.

25 Therefore the present invention contemplates the provision of an extremely simplified and inexpensive means of accurately taking the measurements of the grip of an individual player with the idea of supplying him with clubs which meet 30 his specifications in the size of the grips, as a supplement to the known practice of measuring the length of shaft and over-all weight of clubs.

In the drawing forming a part hereof,

Figure 1 is a side elevation of a golf grip gauge 35 constructed according to the present invention,

Figure 2 is a disassembled view of the subject matter of Figure 1,

Figure 3 corresponds to Figure 1 with the exception that part of the device is shown in section, and

Figure 4 is a section along the lines 4—4 of Figure 1.

The numeral 10 designates a tapered member having a threaded connection with a golf club shaft 11 to which a conventional head (not shown) is attached. The member 10 is tapered downwardly to a boss 12 from which a screw 13 projects. The screw 13 is adapted to engage the internally threaded socket 14, pinned or otherwise secured to the end of the golf shaft 11, as at 15. A spring metal shell 16 encompasses the tapered member 10 and abuts the flange 17 at the top of the socket 14.

55 The outer end of the tapered member 10 is re-

duced and knurled to provide a convenient turning knob 18.

Diametrical adjustment of the spring metal shell 16 is accomplished by turning the knob 18 to effect axial movement of the tapered member 10 relative to the shaft 11. As screw 13 enters the socket 14, the upper portion of the tapered member 10 enters the shell and causes it to expand. The lower portion of shell 16, which is out of the normal grip area, is caused to expand a 10 minimum amount, co-incidentally with the upper portion of the shell, by downward movement of the boss 12 therein.

Suitable size gradations are marked on the upper end of the tapered member 10, as by the numerical scale 19, and read according to the relative position of the upper end of shell 16. (See Figs. 1 and 2.)

While a preferred form of the invention is illustrated in the accompanying drawing it will be 20 appreciated that the invention may take other forms without departing from the spirit or principle of the same. For this reason I do not wish to be limited to the preferred form only but desire protection according to the full scope of the ap- 25 pended claims.

The invention claimed is:

1. In a golf grip gauge, a spring metal shell, an axially movable tapered member therein, said tapered member having a threaded end, a shaft 30 having an internally threaded socket thereon engaging the threaded end on said tapered member, and means on said socket for preventing relative longitudinal movement of said shell with said tapered member upon the engagement of said threaded end of said tapered member and said socket.

2. In a golf grip gauge, a spring metal shell, an axially movable tapered member therein, said tapered member having a threaded end, an internally threaded socket member engaging the threaded end on said tapered member, and means on said socket member for preventing relative longitudinal movement of said shell with said tapered member upon the engagement of said threaded end of said tapered member and said socket.

3. In a golf grip gauge, a spring metal shell defining a normal grip area, an axially movable tapered member therein, said tapered member having a threaded end, an internally threaded socket member engaging the threaded end on said tapered member, and means on said socket member for preventing relative longitudinal movement of said shell with said tapered member 50

upon engagement of said threaded end of said tapered member and said socket.

4. In a golf grip gauge, a spring metal shell defining a normal grip area, an axially movable tapered member therein having a threaded end and a boss adjacent thereto, an internally threaded socket member engaging the threaded end on said tapered member, and a flange at the top of the socket member abutting the end of said shell to prevent relative longitudinal movement thereof upon engagement of said threaded end of the tapered member on said socket.

5. In a golf grip gauge, a spring metal shell defining a normal grip area, an axially movable tapered member therein having a threaded end and a boss adjacent thereto, an internally threaded socket member engaging the threaded end on said tapered member, a flange at the top of the

socket member abutting the end of said shell to prevent relative longitudinal movement thereof upon engagement of said threaded end of the tapered member and said socket, and a scale at the upper end of said tapered member coacting with the top of said shell to indicate diametrical adjustment thereof by axial movement of said tapered member with respect to said socket member. 5

6. In a golf grip gauge, a spring metal shell, an axially tapered member therein, said tapered member having a threaded end, a threaded socket member engaging the threaded end of said tapered member, and a shoulder on the socket member abutting the end of said spring metal shell. 10 15
